CLAIM

The ornamental design for a stethoscope identification tag, as shown and described.

DESCRIPTION

FIG. 1 is a perspective view showing a stethoscope identification tag of my new design with the broken lines representing a segment of a stethoscope tube provided for illustrative purposes only and forming no part of the claimed design;

FIG. 2 is a front elevational view of the stethoscope identification tag of FIG. 1;

FIG. 3 is a top plan view of the stethoscope identification tag of FIG. 1, the bottom plan view being a mirror image;

FIG. 4 is a first side elevation of the stethoscope identification tag of FIG. 1;

FIG. 5 is an opposite second side elevation of the stethoscope identification tag of FIG. 1; and,

FIG. 6 is a rear elevational view of the stethoscope identification tag of FIG. 1.
